(57) **CLAIM**

The ornamental design for a camp cart as shown and described.

DESCRIPTION

FIG. 1 is a front, top, and right perspective view of a camp cart showing my new design;

FIG. 2 is a front, bottom, and right perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The dash-dash broken lines in the drawings depict portions of the camp cart that form no part of the claimed design. Shadows and reflections do not represent any particular color, material, texture or finish.
